UNITED STATES PATENT OFFICE

2,502,643

NEUTRALIZATION OF ALKYL PYRIDINIUM CHLORIDES

Lawrence A. Dirnberger, Berea, Ohio, assignor to
 E. I. du Pont de Nemours & Company, Wil-
 mington, Del., a corporation of Delaware

Application September 30, 1947, Serial No. 776,896

1 Claim. (Cl. 260—290)

1

This invention relates to a process for making neutral alkyl pyridinium chlorides, and relates more particularly to a process for production of alkyl pyridinium chlorides in which trisodium phosphate is used for neutralization of acidic solutions containing alkyl pyridinium chlorides. This invention further relates to the alkyl pyridinium chlorides so produced.

Known processes for the manufacture of neutral alkyl pyridinium chlorides are inadequate, and the products are unsatisfactory. When caustic soda is used for neutralization, alkyl pyridinium chlorides are highly alkaline and undergo considerable pH variation on standing. The alkalinity causes substantial blackening of product. In addition, the manufacturing process is difficult to control. The process is expensive because large quantities of decolorizing agent are required for treatment of the discolored product.

It is an object of this invention to provide neutral alkyl pyridinium chlorides of good color, purity, and pH stability. It is a further object of this invention to provide an easily-controlled process for making neutral alkyl pyridinium chlorides of high quality. Other objects will appear hereinafter.

The foregoing and other objects are attained by using trisodium phosphate as a neutralizing agent. With the use of trisodium phosphate, there is no rapid increase of pH of solution, there is little discoloration, and the process is readily controlled. A product of enhanced pH stability with a relatively low metal-ion content is obtained.

The phosphate neutralization is performed in ordinary operating equipment. In a batch-type operation, the proper quantity of phosphate is merely poured into the container while the acidic solution is agitated. In a continuous-type operation, the phosphate may be added by piping in a continuous stream. The neutralization may conveniently be terminated at the desired pH, as slight excesses of trisodium phosphate increase the pH of the solution very little.

While the phosphate reaction may be employed for neutralization of any alkyl pyridinium chloride, it is of particular interest in the neutralization of "Lorol" pyridinium chloride. "Lorol" pyridinium chloride substantially comprises a mixture of straight-chain normal alkyl pyridinium chlorides whose alkyl groups contain an even number of carbon atoms in the range of 10 to 18. For example, the "Lorol" group is a mixture containing the decyl, dodecyl, tetradecyl,

2

hexadecyl, and octadecyl groups in varying quantities. A large proportion of "Lorol" pyridinium chloride comprises dodecyl pyridinium chloride. The average chain length in the "Lorol" group approximates 13.2 carbon atoms.

In the manufacture of "Lorol" pyridinium chloride, the crude materials are pyridine and "Lorol" chloride. A mixture comprising approximately 2 mols of pyridine per mol of "Lorol" chloride is placed in a reaction tank. The temperature is elevated and the reaction proceeds to a yield of approximately 75%. The mixture is then heated to distill out excess pyridine. The high distillation temperature causes a partial decomposition of unreacted "Lorol" chloride, and releases small quantities of hydrochloric acid and unsaturated hydrocarbons such as dodecene. As a result, subsequent dilution of the reaction mass forms an acidic solution. The acidity is neutralized by addition of measured amounts of trisodium phosphate. The neutralization process may be completed in one step or it may be interrupted while the solution is still acidic, so that further purification may be employed before the solution is completely neutral. In any event, after final neutralization, the pH of the product remains constant at approximately 7.0. Experimental results show that caustic-neutralized "Lorol" pyridinium chloride exhibits a pH variation as high as 1.5 per month of standing, while the maximum variation in trisodium phosphate-neutralized product is 0.1 pH. Many samples of the trisodium phosphate-neutralized material show practically no pH variation.

While the manufacture of neutral "Lorol" pyridinium chloride, using trisodium phosphate, may be carried out in different ways, and may be varied to fit the available equipment, it is a preferred embodiment of this invention to perform the operation in accordance with the example which is depicted on the appended flow sheet.

In step 1, "Lorol" chloride and pyridine are refluxed with agitation at a temperature of 245° to 275° F. for a period of about seven hours. In this step, the principal reaction takes place.

In step 2, the temperature is increased to approximately 350° F. for three hours, and the excess pyridine is distilled off and is recovered by condensation for recycling in the process. The high temperatures in this step cause partial decomposition of "Lorol" chloride, and the mix becomes acidic.

In step 3, the mixture is agitated by intimate contact with saturated steam in order to remove residual pyridine and "Lorol" chloride. This

sparging step continues for approximately three hours.

In step 4, the mix is diluted to a strength of about 45% by straight addition of water.

In step 5, activated carbon of the type ordinarily used for absorbing solids is added. It is effective in decolorizing the solution, and also absorbs metallic ion impurities. The mixture is agitated for about 45 minutes.

In step 6, the acidic solution is neutralized by addition of controlled amounts of trisodium phosphate. A technical grade of trisodium phosphate is sufficiently pure. The trisodium phosphate addition is stopped when the solution reaches a pH of approximately 5. Trisodium phosphate also purifies the "Lorol" pyridinium chloride by precipitating iron, copper, and nickel ions. Experimental results indicate a reduction in copper ion concentration from 84 parts per million to 3 parts per million by use of trisodium phosphate. When caustic soda is utilized for neutralization, the copper ions remain in solution.

The partial neutralization is particularly advantageous because it makes possible the use of stainless steel filtering equipment in step 8.

In step 7, the solution is sparged with steam to remove residual "Lorol" chloride and pyridine. This step also removes pyridine which has been in the form of pyridine hydrochloride, but was liberated by the partial neutralization in step 6.

In step 8, a diatomaceous earth filter aid is added and the solution is filtered in order to remove insoluble impurities. Impurities adsorbed on the activated carbon are also removed.

In step 9, a fresh charge of activated carbon is added. The mixture is agitated for about 45 minutes.

In step 10, the solution is completely neutralized by addition of trisodium phosphate. The step is carried out in a manner similar to step 6, and trisodium phosphate addition is stopped at a pH between 6.5 and 7.5, and preferably at 7.0. When trisodium phosphate is used, there is little danger of obtaining a highly alkaline solution. Addition of a 10% excess of trisodium phosphate produces a pH of only 7.3.

The low pH obtained by using trisodium phosphate is advantageous in several ways. The extent of discoloration appears to depend upon pH, and discoloration is minimized or prevented by keeping the pH low.

The elimination of high pH also allows a wider choice of materials of construction for the sparg-

ing equipment. For example, a bricklined sparge kettle may be employed for all sparging operations, since it is not corroded by acid solutions.

In step 11, the solution is again sparged with steam for removal of objectionable odor.

In step 12, a diatomaceous earth filter aid is added and the solution is filtered in order to remove impurities adsorbed on the activated carbon.

In step 13, the pH of the purified "Lorol" pyridinium chloride is adjusted by addition of trisodium phosphate or phosphoric acid. The product is a viscous light-colored solution, relatively free from odor. The concentration of the solution may be adjusted as desired. The stable neutrality of the phosphate-neutralized material also widens the field of application in packaging.

The solution may be concentrated by vacuum drying, and neutral "Lorol" pyridine chloride may be cast in solid form.

I claim:

In a process for making purified neutral dodecyl pyridinium chloride from dodecyl chloride and pyridine, the steps comprising treating a crude acidic dodecyl pyridinium chloride solution with activated carbon for decolorizing and removing impurities, adding trisodium phosphate until the pH of the solution is 4.5-5.5, sparging with steam, filtering to remove activated carbon and impurities, agitating the filtrate with activated carbon, adding trisodium phosphate until the pH of the solution is 6.5-7.5, sparging with steam, and filtering.
